CLAIM

The ornamental design for a display screen or a portion thereof with graphical user interface, as shown and described.

DESCRIPTION

FIG. 1 is a view of a display screen or a portion thereof with graphical user interface;

FIG. 2 is a view thereof, shown in an alternate environment; and,

FIG. 3 is a view of a second embodiment thereof.

The outer broken line represents a display screen or a portion thereof and forms no part of the claimed design. The broken line showing of the remainder of the graphical user interface forms no part of the claimed design.
